ELECTRIC SWITCH

Tomlinson F. Johnson, Atlanta, Ga.

Application April 19, 1938, Serial No. 202,950

13 Claims.

(Cl. 200—48)

This invention relates to electric switches and aims, among other objects, to provide a novel high tension electric switch of the type having a ventilated blade and provided with novel operating means to retract and advance the blade axially and swing it to open and closed positions. Another aim is to provide a relatively simple, inexpensive and rugged switch structure of this type which permits maximum contact pressure between the jaw and the blade and larger contacts to be used.

Other aims and advantages of the invention will appear in the specification, when considered in connection with the accompanying drawings, wherein:

Fig. 1 is a side elevation of a single phase switch embodying the invention;

Fig. 2 is a top plan view of the switch shown in Fig. 1;

Fig. 3 is a similar top plan view showing the switch blade retracted;

Fig. 4 is a fragmentary sectional view taken on an enlarged scale on the line 4—4 of Fig. 2;

Fig. 5 is a sectional view taken on the line 5—5 of Fig. 4;

Fig. 6 is a fragmentary sectional view similar to Fig. 4 showing the parts in a different position; and

Fig. 7 is an enlarged sectional view taken on the line 7—7 of Fig. 1.

Referring particularly to the drawings, the single phase switch there shown is mounted on a channel support 10 and two stationary insulators 11 and 12. It is adapted to be operated by a third insulator 13 which is mounted for rotation relative to the supporting channel, carrying a stub shaft 14 at the top and an operating crank arm 15. It will be understood that switches of this type are mounted in gangs, three such units being employed in a three phase system and adapted to be operated manually by well known mechanism (not shown).

The insulator 11 is shown as having a bracket 16 to which a pair of horizontal spring plates 17 are connected. These spring plates are split at their forward ends and carry pairs of opposed jaws or contacts 18, the arrangement being such that the jaws present a maximum contact area and each jaw part is free to adjust itself upon and engage the switch blade. The bracket also carries the usual upstanding arcing horn 19 and a line connecting lug or bracket 20.

The switch is shown as having a saddle shaped bracket 21 pivoted to a pair of arms 22 on a cap plate 23 of the insulator 12 and carrying a pipe blade 24 with a flattened contact end 25 best shown in Figs. 2 and 3. The forward end portion of the blade also carries an arcing horn 26 secured to a clamping collar 27. The rear end

of the switch blade is shown as being connected for parallel swinging movement relative to the bracket 21 by means of pairs of parallel links 28 pivoted at their lower ends to ears 29 on the bracket and at their upper ends to a saddle block 30 secured by bolts 31 to the switch blade. The arrangement is such that when the parallel links are swung to their forward position as shown in Figs. 1, 2 and 4, the blade 24 is advanced to its closed position and, when they are swung rearwardly as shown in Figs. 3 and 6, the blade is retracted from the jaw. At the contact end, this movement is substantially axial. When the blade is retracted, it is free to swing to its open position.

The cap member on the stationary insulator 12 has pairs of rearwardly extending arms 32, to the rearward ends of which brace bars 33 in the form of copper conductors are connected and extend to the top of the rotatable insulator 13 and their rear ends are secured to forwardly extending arms 34 connected to an upper bearing member 35 around the stub shaft 14 on said insulator. The member 35 has a line connecting lug 36 which is electrically connected to the rear end of the switch blade by a braided conductor 37 connecting the saddle block 30 to one of the bars 33.

To operate the switch blade an arm or crank 38 is secured to the stub shaft 14 and carries a double jointed link 39 which is pivotally connected at its forward end to upstanding ears 40 on the saddle block 30. The arrangement is such that when the crank arm 38 is turned clockwise as viewed in Figs. 2 and 3, it will exert a horizontal pull on the switch blade and swing it rearwardly on the two pairs of links 28 until the rear end of the blade again rests in the saddle bracket as shown in Fig. 6, with the blade tip fully withdrawn from the jaw, as shown in Fig. 3.

To hold the switch blade and its bracket in its horizontal position while the blade is being retracted or advanced as well as while in closed position, there is shown a pair of opposed upstanding arms 41 rigidly connected relative to the saddle bracket 21 by means of bolts 42 carrying bushings 43 on which the parallel links 28 are pivoted. A crank arm 44 above the operating crank 38 is mounted for relative rotation on the stub shaft 14 and a second double jointed link 45 carried by the same arm is pivotally connected at its forward end to a cross bar 46 pivotally mounted between the upper ends of the upstanding arms 41. The link 45 and its arm 44 not only act as a limiting stop to hold the switch blade and its saddle bracket 21 horizontal but also as a stiff leg to prevent the pivoted joint or tending to swing the blade vertically until it is fully re-

tracted. This arrangement permits the full power applied to the operating arm 38 to be transmitted to the switch blade either to retract or advance it and this is quite advantageous in cold climates when ice accumulates on the switch jaws. However, it is to be understood that the switch jaws may be and usually are covered with ordinary sleet hoods.

Referring to Figs. 1, 3 and 4, the operating arm 10. 38 is shown as having a strap metal finger 47 secured to it intermediate its ends and extending laterally in a counterclockwise direction, as viewed in Figs. 2 and 3. It has an upstanding bent end 48 to engage one side of the freely rotatable arm 44 and break the stiff leg joint just before the operating arm 38 reaches its blade opening position, the purpose being to permit the continued movement of the operating arm 38 to impart vertical swinging movement to the switch 15 blade and its connected parts. The horizontal pivots of the double joints in the operating links permit this swinging movement, the parts being shown in their fully operated positions by dotted lines in Fig. 4. It will be observed that the rear 20 end of the switch blade remains in its retracted position within the saddle bracket when it is in its fully opened position because the pivoted connecting members at the forward ends of the two 25 links 39 and 45 are closely adjacent to each other and any tendency of the link 39 to pull the blade out of its saddle is resisted by the upper link 30 joint. Also, the weight of the blade 24 tends to hold it in its retracted saddle engaging position 35 by gravity. It will remain in this seated position due to gravity until it swings to the horizontal position (Fig. 6).

To close the switch, it will be understood that the insulator 13 is turned in a counterclockwise direction as viewed in Figs. 2 and 3 and, after the 40 blade swings to its horizontal position, the link 39 imparts forward axial movement to the blade and the operating parts, straightening out the link 45 to its stiff leg position (shown in Figs. 2 and 4), when said link locks the blade closed. During 45 the final movement of the operating arm 38, the parallel links 28 swing to their forward positions as shown in Figs. 1, 2 and 4. It will be observed that when the blade and the saddle bracket are 50 in the horizontal position, the mechanical advantage of the operating arm is increased because the effective lever arm is decreased. This is a very decided advantage because it enables the operating arm to exert a powerful closing thrust on the 55 blade so that spring jaws with large contact areas may be employed.

Referring to Fig. 7, the crank arm 14 for operating the rotatable insulator 13 is shown as having radial lugs or ears 49 carrying adjustable stop 60 members in the form of set screws 50 cooperating with stationary abutments 51 secured to the supporting channel 10. It will be understood that these stop members are so adjusted as to limit the rotation of the insulator and operating arm 38. 65 This arrangement makes it impossible for an attendant to operate the switch in the wrong direction.

From the foregoing description, it will be seen that the improved switch is very simple and 70 rugged in its construction and effective in its operation. It is well adapted for use on high tension transmission systems in all climates. There are no delicate parts which require frequent adjustment, replacement or repairs. It may be manufactured and installed at a relatively low

cost. In fact, such switches are eminently adapted for use on all high tension systems.

Obviously, the present invention is not restricted to the particular embodiment thereof herein shown and described. Moreover, it is not indispensable that all the features of the invention be used conjointly, since they may be employed advantageously in various combinations and sub-combinations.

What is claimed is:

1. In an electric switch of the character described, a pair of spaced supporting insulators; a jaw mounted on one of said insulators; an axially retractable and swinging blade mounted on the other insulator; a rotatable operating insulator having blade actuating means connected to impart said movements to the blade; and a jointed stiff leg also connected to the rotatable insulator and associated with the blade normally to maintain the blade in switch closing position and to prevent swinging movement of the blade until it is retracted.

2. In an electric switch of the character described, a pair of spaced supporting insulators; a jaw mounted on one of said insulators; an axially retractable and swinging blade mounted on the other insulator; a rotatable insulator mounted adjacent to said blade supporting insulator; a crank arm and double jointed operating link connecting said rotatable insulator to the blade to impart both retracting and swinging movement thereto; and a double jointed stiff leg also carried by the rotatable insulator and connected to limit the swinging movement of the blade and preventing the operating link from swinging the blade before it is retracted from the jaw.

3. In an electric switch of the character described, a pair of spaced supporting insulators; a jaw mounted on one of said insulators; an axially retractable and swinging blade mounted on the other insulator; a rotatable insulator mounted adjacent to said blade supporting insulator; a crank arm and double jointed operating link connecting said rotatable insulator to the blade to impart both retracting and swinging movement thereto; a second arm freely rotatable with respect to said rotatable insulator; a double jointed stiff leg link connected to limit the swinging movement of the blade toward closed position and permitting axial movement only to be imparted to the blade; and means on the operating arm to break the stiff leg link and thereby permit opening swinging movement to be imparted by the operating link to the blade after it is retracted.

4. In an electric switch of the character described, a pair of spaced supporting insulators; a jaw mounted on one of said insulators; an axially retractable and swinging blade mounted on the other insulator; a rotatable insulator mounted adjacent to said blade supporting insulator; a crank arm and double jointed operating link connecting said rotatable insulator to the blade to impart both retracting and swinging movement thereto; and means also carried by said rotatable insulator to limit the closing swinging movement of the blade and hold it in position to register with the jaw so that axial closing and retracting movements only may be imparted to the blade while it is so held.

5. In an electric switch of the character described, a pair of spaced supporting insulators; a jaw mounted on one of said insulators; an axially retractable and swinging blade mounted on the other insulator; a rotatable insulator mounted adjacent to said blade supporting insu-

- lator; a crank arm and double jointed operating link connecting said rotatable insulator to the blade to impart both retracting and swinging movement thereto; a double jointed stiff leg member also carried by the rotatable insulator and connected to prevent the blade from swinging while the operating link is retracting it; and means associated with the crank connected to break the stiff leg and permit the operating link to impart swinging movement to the blade after it is retracted.
6. In an electric switch of the character described, a pair of spaced supporting insulators; a jaw mounted on one of said insulators; an axially retractable and swinging blade mounted on the other insulator; a rotatable operating insulator having blade actuating means connected to impart said movements to the blade; and means also carried by said rotatable insulator to support and limit the closing swinging movement of the blade and hold it in position to register with the jaw so that axial closing and retracting movements may be imparted to the blade while it is so held.
7. In an electric switch of the character described, a pair of spaced supporting insulators; a jaw mounted on one of said insulators; an axially retractable and swinging blade mounted on the other insulator; a rotatable operating insulator having blade actuating means connected to impart said movements to the blade; an arm freely rotatable with respect to said rotatable insulator; a double jointed stiff leg link connected to limit the swinging movement of the blade toward closed position and permitting axial movement only to be imparted to the blade; and means on the operating arm to break the stiff leg link and thereby permit opening swinging movement to be imparted by the operating link to the blade after it is retracted.
8. In an electric switch of the character described, a pair of spaced supporting insulators; a jaw mounted on one of said insulators; an axially retractable and swinging blade mounted on the other insulator; a rotatable operating insulator having blade actuating means connected to impart said movements to the blade; a double jointed stiff leg member also carried by the rotatable insulator and connected to prevent the blade from swinging while the operating link is retracting it; and means connected to break the stiff leg during the final retracting movement of the blade and permitting the operating link to impart swinging movement to the blade after it is retracted.
9. In an electric switch of the character described, a pair of spaced supporting insulators; a jaw mounted on one of said insulators; a blade support pivotally connected to the other insulator; pairs of parallel pivoted links on the support; a blade connected to said links so that it is capable of both axial and swinging movement; an operating insulator having actuating means connected to said blade; and a stiff leg carried by said operating insulator and connected to said pivoted support causing said actuating means to impart retracting movement only to the blade when it is closed.
10. In an electric switch of the character described, a pair of spaced supporting insulators; a jaw mounted on one of said insulators; a blade support pivotally connected to the other insulator; pairs of parallel pivoted links on the support; a blade connected to said links so that it is capable of both axial and swinging movement; an operating insulator having actuating means connected to said blade; and a stiff leg carried by said operating insulator and connected to said pivoted support causing said actuating means to impart retracting movement only to the blade when it is closed.
11. In an electric switch of the character described, a pair of spaced supporting insulators; a jaw mounted on one of said insulators; a blade support pivotally connected to said second insulator; pairs of parallel pivoted links on the support; a blade connected to said links to permit both axial and swinging movement of the blade; a rotatable insulator mounted adjacent to the blade supporting insulator; a crank arm and double jointed operating link connecting said rotatable insulator to the blade to impart both retracting and swinging movement thereto; and a double jointed stiff leg parallel with said operating link connected to limit the swinging movement of the blade and preventing the operating link from swinging the blade before it is retracted from the jaw.
12. In an electric switch of the character described, a pair of spaced supporting insulators; a jaw mounted on one of said insulators; a blade support pivotally connected to said second insulator; pairs of parallel pivoted links on the support; a blade connected to said links to permit both axial and swinging movement of the blade; a rotatable insulator mounted adjacent to the blade supporting insulator; a crank arm and double jointed operating link connecting said rotatable insulator to the blade to impart both retracting and swinging movement thereto; a second arm freely rotatable with respect to said rotatable insulator; a double jointed stiff leg link parallel with the operating link connected to limit the swinging movement of the blade toward closed position and permitting axial movement only to be imparted to the blade; and means on the operating arm to break the stiff leg link and thereby permit opening swinging movement to be imparted by the operating link to the blade after it is retracted.
13. In an electric switch of the character described, a pair of spaced supporting insulators; a jaw mounted on one of said insulators; a blade support pivotally connected to said second insulator; pairs of parallel pivoted links on the support; a blade connected to said links to permit both axial and swinging movement of the blade; a rotatable insulator mounted adjacent to the blade supporting insulator; a crank arm and double jointed operating link connecting said rotatable insulator to the blade to impart both retracting and swinging movement thereto; a second arm freely rotatable with respect to said rotatable insulator; a double jointed stiff leg link connected to limit the swinging movement of the blade toward closed position and permitting axial movement only to be imparted to the blade; means on the operating arm to break the stiff leg link and thereby permit opening swinging movement to be imparted by the operating link to the blade after it is retracted; and stop means to limit the operating movement of said rotatable insulator.

TOMLINSON F. JOHNSON.
